ROBERT L. DAVIS, OF PITTSBURGH, PENNSYLVANIA, ASSIGNOR TO WESTINGHOUSE ELECTRIC & MANUFACTURING COMPANY, A CORPORATION OF PENNSYLVANIA

HIGH FREQUENCY RADIO CIRCUITS

Application filed March 27, 1928. Serial No. 265,020.

My invention relates to amplifiers and particularly to amplifiers for use with very high frequencies.

It is customary to so arrange vacuum-tube amplifiers that a high direct-current potential must be impressed upon the plates. If the amplifiers are of the high-power type, requiring that cooling water be supplied to the plates, it has heretofore been necessary to supply the water through a long rubber hose, or other insulating pipe, in order that the resistance of the long column of water shall prevent leakage of the direct-current, and of the alternating current, to ground.

Partly, in order to prevent the passage of radio-frequency current and partly to save space, the long hose is usually in the form of a coil. When high frequencies are employed, the distributed capacity of the coiled hose filled with water is sufficient to interfere with effective insulation of the radio-frequency potential from the ground.

My invention avoids this difficulty by so re-arranging the amplifier circuits that the anodes shall be nearly at ground potential, as regards radio frequency. For this purpose, it is necessary that the cathodes be at a high radio-frequency potential relative to the ground. This requires that the cathodes be separated from the cathode-heating supply means by choke coils.

It is an object of my invention to provide an oscillating circuit in which the inductance of said choke coils shall serve as the tuning inductance.

It is a further object of my invention to provide an arrangement in which the inductance in the output circuit shall comprise two inductors in parallel and the total inductance be thereby reduced.

It is a further object of my invention to provide an arrangement in which the inter-electrode capacity of the tube and the inductance of the choke coils shall constitute elements of the tuned circuit.

It is a further object of my invention to arrange a push-pull amplifier in such a way that the anodes shall be connected to a point of ground potential in the input circuit

and the cathodes shall be separate from the input circuit.

Other objects of my invention and details of the construction will be readily understood from the following detailed description and the accompanying drawing, in which the single figure is a diagram of the circuits and apparatus.

In the drawing, the input circuit is composed of an inductor 1 and a tuning capacity comprising two condensers 2, mechanically connected to be adjusted simultaneously. The point between these two condensers may be connected to ground or to a source of extra signalling current, if desired.

The midpoint of the inductor 1 is connected through a register 3 to a ground connection 4. The connection includes a C-battery 5 and a condenser 6 in parallel. The condenser is of sufficient capacity to act as a connection of substantially zero impedance for the frequency to which the circuit 1-2 is tuned. From two adjustable points near the extremities of the inductor 1, connections 7 and 8 extend to the grids 9 and 10 of two amplifier tubes 11 and 12, the anodes 13 and 14 of these tubes are connected together by a conductor 15 and from this conductor through a stopping condenser 16 and a damping resistor 17 to the ground connection 4 and to the negative end of a B-battery 18. The positive end of the B-battery is connected through a radio frequency choke 19 to the conductor 15. The condenser 16 prevents the short circuit of the battery 18, but is large enough to offer no substantial impedance to the high-frequency currents in the tubes. The resistor 17 is of sufficient magnitude to prevent any substantial flow of currents of parasitic frequencies.

The cathodes 20 and 21 of the two tubes are illustrated as ordinary filaments. If desired, filamentary or other heating members may be employed, distinct from the cathodes themselves. If this is done, the cathode proper should be connected to the midpoint 22, in the case of the tubes 11 and 23, in the case of the tube 12. These midpoints are established by connecting a pair of condensers across the cathode-heating circuit, that is,

across the terminals of the filamentary cathode or heater.

An adjustable condenser 24 is connected between the midpoint 22 and the anode 13 and a similar adjustable condenser 25 is connected between the midpoint 23 and the anode 14. The capacities of the condensers 24 and 25 are in parallel, respectively, with the inter-electrode capacities of the tubes 11 and 12.

The source of heating energy may be either direct current or low-frequency alternating current. The latter is chosen for illustration and is supplied through a transformer 29. The midpoint of the secondary 30 of this transformer is grounded as indicated at 31 and the terminals of the secondary are connected, respectively, to midpoints of two inductors 32 and 33.

The inductor 32 is connected in a lead extending from one terminal of the filament 20 to one terminal of the filament 21 and the inductor 33 is similarly connected from the other terminal of the filament 20 to the other terminal of the filament 21. The inductors 32 and 33 in parallel constitute the tuning inductance as explained below. It is not necessary that they have as great inductance as would be required if they were to act as a choke coil to prevent the high-frequency potential present upon the cathodes 20 and 21 from passing to the transformer-secondary 30 and thence to ground.

The midpoints of the inductors 32 and 33 are connected also to a pair of condensers establishing a midpoint 34 which is connected to the grounded terminal of the resistor 17.

Output leads 36 are connected from two separated points upon either the inductor 32 or the inductor 33.

A neutralizing condenser 37 is connected between the midpoint 23 associated with the tube 12 and the grid 9 of the other tube 11. It is thus connected to the conductor 7 and so to that end of the inductor 1 opposite the connection to the grid 10. Similarly, a neutralizing condenser 38 is connected between the midpoints 22 and the grid 10 and thus, through the conductor 8, to that end of the inductor 1 opposite the connection to the grid 9.

In the event that the inductance in the inductors 32 and 33 must be greater than is desired for tuning purposes, in order to effect the necessary separation, at radio frequency, between the transformer 29 and the filaments, these inductors may be made smaller than this requirement indicates and supplemented by inductors 40 and 41 between the midpoints of the inductors 32 and 33 and the terminals of the secondary 30. The supplemental inductors may, if desired, be retained even when the tuning inductors are large.

In the operation of the device, direct-cur-

rent potential is impressed upon the anodes 13 and 14 from the battery 18. The direct-current circuit is completed from the cathodes 20 and 21 to the midpoints of the inductors 32 and 33 and thence to the ground at 31, returning to the battery 18 from the ground connection 4.

In order that direct current shall pass over this circuit, the cathodes must be heated. If the cathodes are the filaments themselves, they are heated by the current from the transformer 29 over a circuit through inductor 41 and the two halves of the inductor 32 in parallel to the two filaments, returning from the filaments over the two halves of inductor 33 to the midpoint thereof and from thence through the inductor 40 to the opposite terminal of the secondary 30. If the filaments 20 and 21 are not themselves the cathodes, the circuit just traced conveys heating current to them and they in turn heat the cathodes.

The potentials of the grids 9 and 10 are varied simultaneously and in opposite phase by the current in the resonant circuit 1-2. Direct-current potential is impressed on both grids alike by the battery 5. The high-capacity condenser 6 ensures that the radio-frequency potential of the midpoint of inductor 1 is fixed and the resistor 3 prevents the development of parasitic oscillations.

The plates 13 and 14, being maintained at a fixed potential as regards the radio frequency by the connection extending through conductor 15, condenser 16 and resistor 17 to the ground connection 4, are at ground potential as regards radio frequency. Any arrangement for cooling the tubes need only provide against leakage of direct current. Water supplied through a coiled hose is, therefore, satisfactory for cooling the plates even when the very highest frequencies are contemplated.

The resistor 17 acts to prevent the development of parasitic oscillations and also conducts to ground any small high-frequency currents which result from the capacity within one tube not exactly matching that within the other.

Since the plates are at a fixed potential, the difference in potential between plates and filaments, which results from the alternating-current potential impressed upon the grids, will be manifested as radio-frequency potential changes upon the cathodes. These potential changes will be greater than the potential changes upon the grids because of the ordinary amplifying action of the tubes. Amplified radio-frequency current will thus be set up in the output circuits of the device.

For the tube 11, the output circuit extends through the inter-electrode capacity of the tube to the cathode 20, thence through the upper halves of inductors 32 and 33 in parallel and through the centering condensers to the point 34, thence over the resistor 17 and

through the large condenser 16 to the plate 13. A similar circuit through the inter-electrode capacity of the tube 12 may be traced over the two lower halves of the inductors 32 and 33 in parallel to the point 34 and so to the plate 14.

It is not necessary to consider the two output circuits traced above separately. One output circuit for the two tubes may be traced, including all of inductor 32 in parallel with inductor 33 as the inductance and the inter-electrode capacity of tube 11 in series with that of tube 12 as the capacity. Since in this circuit the inductance is twice 15 and the capacity half that for the circuit first considered, the frequency is the same.

Whether the output be considered as two tuned circuits or one, it is a parallel-resonant circuit in either case and therefore acts to 20 prevent radio-frequency currents reaching the transformer. The inductors 32 and 33 therefore need not be designed as if they were to act as choke coils.

Because the potentials upon the grids 9 25 and 10 are in opposite phase, the currents set up in the two output circuits just traced produce additive effects in the output connections 36. The radio-frequency current or potential introduced at the input results, therefore, in amplified radio-frequency current or potential in the output.

The action of the resistor 17 in the two oscillating circuits just traced is sufficient to prevent the circuits from oscillating at para- 35 sitic frequencies.

Further prevention of undesired oscillations is effected by the neutralizing condensers 37 and 38. The potential changes on the cathode 21 may be regarded as the 40 output of a generator between the plate 14 and the cathode. The condenser 37 establishes a connection from the cathode 21, that is, from one terminal of said generator, to the conductor 7 and so to the upper part of 45 the inductor 1. The current in this connection flows through the upper part of the inductor 1, the resistor 3, condenser 6, resistor 17 and condenser 16 to the plate 14, which is the other terminal of said generator.

50 The inductor 1, acting as an auto-transformer, impresses corresponding but opposite potentials upon the conductor 8. The potential thus impressed upon the grid 10 through the condenser 37 and over the conductor 8 is, therefore, opposite in phase to the potential impressed upon the grid 10 through the inter-electrode capacity between the cathode 21 and the grid 10. Consequently, by properly adjusting the condenser 37, 55 the tendency of the tube 12 to produce self-oscillation may be neutralized. In the same way, the condenser 38 may prevent the spontaneous generation of oscillation by the tube 11.

60 The inter-electrode capacity, which is in

series with the upper halves of the inductors 32 and 33 in parallel, consists of the capacity between the cathode and the grid, in series with the capacity between the grid and the plate, plus the capacity between the filament 70 and the plate directly. The resultant of these capacities, with the inductance resulting from the parallel connection, determines the frequency of the tuned output circuit. If this frequency is too high, the capacity within 75 the tube may be supplemented by the capacity of the adjustable condenser 24. Similarly, the capacity within the tube 12 may be supplemented by the adjustable capacity of the condenser 25. By means of these adjustable 80 condensers, any inequality between the capacities of the two tubes may be compensated.

On the other hand, if the frequency is too low, the condensers 24 and 25 may be omitted 85 altogether. If, then, the frequency is still too low, the inductance of the two halves of coils 32 and 33, in parallel, which constitutes the inductance in one of the tuned circuits may be further diminished by so placing the 90 coils that the mutual inductance between them tends to diminish the combined inductance of the two in parallel. That is, one coil should be so placed that the flux established thereby shall act, not additively, but 95 subtractively upon the flux in the other coil established by the current from the common lead.

In the usual connection for amplifiers, the capacity which must be neutralized to prevent re-generation is the capacity between the grid and the plate. In the connection here described, the capacity which must be neutralized to prevent re-generation is the capacity between the grid and the filament. 100 This is much smaller than the capacity between the grid and the plate. The difficulty in neutralizing the tendency to re-generation due to capacity within the tube is, therefore, 105 less with the arrangement here described. 110

While I have described but one specific embodiment of my invention and have mentioned only a few modifications in the details thereof, many other modifications of the details and many variations in the application 115 of the principle of my invention will be obvious to those skilled in the art. I, therefore, do not intend to be limited except as required by the prior art or indicated in the accompanying claims.

120 I claim as my invention:

1. In an amplifier, an input inductor, a vacuum tube and a tuned output circuit, said input inductor constituting part of the grid-plate circuit and said output circuit including the interelectrode capacity of the tube in series with inductance, only a portion of said inductance being employed to determine the resonant frequency of said output circuit.

2. In a push-pull amplifier, an input in-

ductor, a pair of vacuum tubes, a connection substantially devoid of inductance connecting the plates of said tubes together and to an intermediate point of said inductor.

5 3. In a push-pull amplifier, an input inductor, a pair of vacuum tubes, a connection substantially devoid of inductance connecting the plates of said tubes together and to an intermediate point of said inductor and 10 connections from points of said inductor on opposite sides of said intermediate point to the grids of the respective tubes.

15 4. In a push-pull amplifier, an input inductor, a pair of vacuum tubes, a connection substantially devoid of inductance connecting the plates of said tubes together and to an intermediate point of said inductor, connections from points of said inductor on opposite sides of said intermediate point to the 20 grids of the respective tubes and neutralizing condensers connected between each filament and the grid of the other tube.

25 5. In a vacuum-tube cathode-heating system, a cathode-heating means for each tube, leads connecting the terminals of one cathode-heating means to those of another, an inductor in each lead, a source of heating current and connections from said source to said cathode-heating means through said inductors, and means for separating the radio-frequency component from the direct-current component of the current flowing through 30 said inductors.

35 6. In a vacuum-tube cathode-heating system, a cathode-heating means for each tube, leads connecting the terminals of one cathode-heating means to those of another, an inductor in each lead, a source of heating current and connections from said source to an 40 intermediate point of each inductor, whereby the cathode-heating devices are connected in parallel to the source of heating current, and a capacity connected on one side to the terminals of a cathode-heating means in parallel and on the other side to intermediate points of the respective inductors in parallel, whereby said capacity and the parallel-combined inductance of portions of two of said 45 inductors constitute a tuned circuit.

50 7. In a push-pull amplifier, an input circuit, a source of heating current, two vacuum tubes having their anodes connected together and to the input circuit, cathode heating means for each vacuum tube means including inductors for connecting said cathode heating means together and to the source of heating current said means also connecting the cathode together through said inductors in parallel.

55 80 In testimony whereof, I have hereunto subscribed my name this 22nd day of March, 1928.

ROBERT L. DAVIS.
